EARRING

Arthur Herman, Brooklyn, N. Y.

Application June 6, 1946, Serial No. 674,800

10 Claims. (Cl. 63—14)

1

This invention relates to earrings.

It is the principal object of my invention to provide an earring which replaceably carries a piece of fabric as its primary ornamental element so that the wearer may have the earring fabric match the fabric of her dress.

It is an ancillary object of my invention to provide an earring comprising relatively few and simple parts and which is economical to manufacture and rugged in use.

Other objects of my invention will in part be obvious and in part hereinafter pointed out.

My invention accordingly consists in the features of construction, combinations of elements and arrangement of parts which will be exemplified in the earring hereinafter described and of which the scope of application will be indicated in the appended claims.

In the accompanying drawings in which is shown one of the various possible embodiments of my invention

Fig. 1 is a front plan view of an earring constructed in accordance with my invention;

Fig. 2 is a sectional view taken substantially along the line 2—2 of Fig. 1, and

Fig. 3 is a perspective view showing the manner in which a piece of fabric is trimmed after being inserted in the earring.

In general, I carry out my invention by providing an earring including, in addition to suitable means to attach the earring to an ear, a member, e. g. a ring, having a through aperture of any desired shape, and a domed element supported substantially centrally of the aperture, with the high point of said element lying to one side of the member and the base of said element lying on the other side of and close to the aperture, there being a slight and approximately uniform clearance between said aperture and said element adjacent its base, so that a piece of fabric draped over said element is caught between the apertured member and base of the element. Optionally, the domed element and apertured member may be interconnected by resilient means in order to pinch the fabric between said element and ring and thereby more securely hold the fabric in place.

Referring now to the drawings, 10 denotes an earring constructed in accordance with my invention and comprising an apertured member 12 and domed element 14. Although the various parts could be forged or cast, for convenience of manufacture, the member, domed element and interconnecting means may be made from a single piece of flat stock blanked, shaped, drawn and

2

bent to obtain the desired configuration illustrated in Figs. 1 and 2. The member 12 desirably is in the shape of a ring of half-round cross section, although it will be understood that any other configuration which presents an attractive, ornamental appearance will serve as well. Thus the member may be flat or of box-shaped cross section, with its rear side open. The central through aperture 16 of the member may be of any desired contour. The contour illustrated is circular, but it is within the scope of my invention to have the said aperture assume any other shape as, for instance, oval, polygonal, stellate or lunulate. Likewise, the outer periphery of the member may have any outline and said member may be ornamented in any desired fashion.

The element 14 has a base of approximately the same configuration as the central aperture 16 in the member 12. As best seen in Fig. 2, said element is domed, that is, its inner portion is higher than its base, there preferably being a smooth curvature connecting the high point of said element to said base. Although this curvature is shown as being entirely convex on the face of the element, it will be understood that such curvature may be concave in parts.

The base of the domed element will, in general, be slightly smaller than the central aperture 16, particularly if the inclination of said element 30 adjacent its base is rather steep, as is the case with the element shown in Fig. 2. This relative dimensioning of the aperture and base of the element is made necessary by the governing consideration that during use there must be a slight 35 clearance between the aperture and the base of the domed element. It is pointed out, nevertheless, that if the element is not very steeply sloped adjacent its base, it is possible for the base of the element to be as large as or even slightly 40 larger than the aperture 16.

It should also be mentioned that, if desired, the domed element may have a flange extending from its base. This flange may either be continuous or, as illustrated herein, may cover only a small 45 part of the periphery of the element, in which case the flange simply comprises a tab 18.

The member and element are interconnected in any suitable fashion, as for example, by a U-shaped shank 20 in one piece with the element 50 and member. Said shank includes a portion extending rearwardly from the external periphery of the member, another portion extending rearwardly from the base of the element and a leg interconnecting said two portions. Optionally, 55 the material from which the member and element

are formed may be of resilient stock, e. g., Phosphor bronze or brass, and in such event the earring is so fashioned that the shank 20 normally biases the domed element to a position wherein its base is further forward with regard to the member than it would be if a piece of fabric were draped over the element. As already noted, this insures a better grip on the fabric.

Some suitable means is incorporated to attach the earring to a wearer's ear. Such means, as shown herein, consists of a conventional ear wire 22, which comprises a U-shaped wire frame, one of whose legs is tapped to receive a threaded pin 24 having a knurled manipulating knob 26 at one end and a pressure pad 28 on its other end. The other leg of the frame is secured, e. g., by welding, to a bridging strip 30 spanning the base of the domed element at its rear.

If desired, said bridging strip, like the other elements of the earring, exclusive of the attaching means, may be formed in one piece with the earring. With such an arrangement, one end of the bridging strip is integral with and extends from the rear edge of the domed element and the other end of the bridging strip is secured as, for instance, by welding to the base of the domed element at a diametrically opposite point.

A piece of fabric is secured to the earring as follows: An edge of the fabric is introduced into the space between the base of the domed element and the aperture 16 in the ring. The fabric is then slid over the domed element until the fabric fully covers said element and substantially completely fills the slight space between said element and ring. At such time the fabric will be secure in its place, that is, it will not slip out accidentally, inasmuch as it is caught between the ring and element. As already noted, insertion of the fabric may slightly spread apart the ring and element so that the fabric will be resiliently held in place. The tab 18 aids in initially guiding the edge of the fabric on to the curved surface of the domed element. It also is pointed out that the fabric tends to jam between the two legs of the U-shaped shank 20, thus further aiding to hold the fabric in position.

After the fabric has been arranged in the foregoing manner, the portions thereof which extend beyond the member 12 may be cut off, as indicated in Fig. 3, so that the only part of the fabric which will be exposed in normal use will be that which covers the domed element and lies within the space defined by the aperture 16.

It will thus be seen that I have provided an earring which achieves the several objects of my invention and is well adapted to meet the conditions of practical use.

As various possible embodiments might be made of the above invention and as various changes

might be made in the embodiment above described, it is to be understood that all matter herein set forth or shown in the accompanying drawings is to be interpreted as illustrative and not in a limiting sense.

Having thus described my invention, I claim as new and desire to secure by Letters Patent:

1. An earring comprising a member having a through aperture, a domed element, the base whereof is of approximately the same configuration as the aperture in said member, said element being supported by the member substantially centrally of said aperture, with a slight clearance between said aperture and said element adjacent its base, so that when a piece of fabric is draped over said element, said fabric will be caught between the base of said element and said aperture, said element being supported independently of the fabric, and means to attach the earring to a wearer's ear.
2. An earring as set forth in claim 1, wherein said member is of ring-like configuration.
3. An earring as set forth in claim 1, wherein the high point of the domed element is disposed on one side of the apertured member and the base of the domed element is disposed on the other side of the apertured member, when a piece of fabric is draped over said element.
4. An earring as set forth in claim 1, wherein resilient means is provided to support the domed element.
5. An earring as set forth in claim 1, wherein the apertured member and domed element are made from a single piece of stock.
6. An earring as set forth in claim 1, wherein the domed element is made of sheet metal.
7. An earring as set forth in claim 1, wherein the domed element and apertured member are made from sheet metal.
8. An earring as set forth in claim 1, wherein the domed element is hollow and has an open rear end.
9. An earring as set forth in claim 1, wherein the base of the domed element is no larger than the aperture in the apertured member.
10. An earring as set forth in claim 1, wherein a tab extends outwardly from the base of the domed element to aid in guiding fabric into place over said element.

ARTHUR HERMAN.
